HANGING CHAIR

Bruce M. Furino, 2839 Lion Heart Road,
Winter Park, Fla. 32789

Filed Oct. 2, 1974, Ser. No. 511,298

Term of patent 14 years

Int. Cl. D6—01

U.S. Cl. D6—47

Fig. 1.

Fig. 2.

*Fig. 3.**Fig. 4.*FIG. 1 is a perspective side view illustrating a hanging chair design of the present invention, in which the pin at the upper extremity is for illustrative purposes only.

FIG. 2 is a front perspective view of the hanging chair in accordance with the present invention.

FIG. 3 is a perspective rear view in accordance with the present invention.

FIG. 4 is a side view of the design in accordance with the present invention, in which the side opposite the illustrated side is a mirror image thereof.

I claim:

The ornamental design for a hanging chair, as shown and described.
